Geo. P. Kimmel.

ATTORNEY.

UNITED STATES PATENT OFFICE.

WILLIAM H. SEABROOK, JR., OF SAVANNAH, GEORGIA.

HAIRDRESSING IMPLEMENT.

Application filed September 24, 1925. Serial No. 38,361.

To all whom it may concern:

Be it known that I, WILLIAM H. SEABROOK, Jr., a citizen of the United States, residing at Savannah, in the county of 5
5 Chatham and State of Georgia, have invented certain new and useful Improvements in Hairdressing Implements, of which the following is a specification.

This invention relates generally to improvements in barbers' and hair dressers' implements, more particularly to a device for taking kinks out of hair, and has for its object to provide, in a manner as herein-after set forth, a device of the class referred 10
15 to, for expeditiously removing kinks from hair without scorching or burning the scalp during the operation of the device.

A further object of the invention is to provide, in a manner as hereinafter set forth, a device of the class referred to, including a heat applying element in the form of a comb, and a guard element associated with the heat applying element, in a manner to prevent the latter from scorching 20
25 or burning the scalp when the heat applying element is passed through the hair to remove the kinks therefrom.

A further object of the invention is to provide, in a manner as hereinafter set forth, a device for the purpose referred to, provided with a guard element and a heat applying element, and with the former so constructed and arranged as to prevent the heating thereof during the heating of the 30
35 heat applying element prior to the application of the latter.

Further objects of the invention are to provide, in a manner as hereinafter set forth, a device for the purpose referred to, which is comparatively simple in its construction and arrangement, strong, durable, compact, thoroughly efficient in its use, conveniently applied to the hair for the removal of kinks therefrom, and comparatively 40
45 inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifi- 50

cations can be resorted to which come within the scope of the claims hereunto appended.

In the drawings wherein like reference characters denote corresponding parts throughout the several views:—

Figure 1 is a side elevation of a hair kink removing device, in accordance with this invention.

Figure 2 is a sectional elevation thereof.

Figure 3 is a fragmentary view, in inverted plan.

Figure 4 is a fragmentary view, in top plan, of the guard.

Figure 5 is a section on line 5—5, Figure 2.

Figure 6 is a section on line 6—6, Figure 2.

Figure 7 is a section on line 7—7, Figure 2.

Figure 8 is a section on line 8—8, Figure 2.

Figures 9, 10, 11 and 12 are respectively sections on lines 9—9, 10—10, 11—11 and 12—12, Figure 2.

Figure 13 is a side elevation of the implement with the guard element shifted from the heat applying element.

A device for removing kinks from hair, in accordance with this invention, comprises a heat applying element and a guard element associated with the heat applying element to prevent the scorching or burning of the scalp during the use of the device. The heat applying element includes a solid metallic body portion 1 of substantial length and which is substantially circular in cross section. Formed integral with and depending from the lower face of the body portion, at the longitudinal center thereof, is a series of tines 2, spaced equi-distant with respect to each other, and said series is positioned between a pair of tapered tines 3, 4, and which are formed integral with the body portion 1, at the ends thereof. The body portion and tines are formed of the same material and provide what may be termed a heat applying member of the comb type.

The outer side edges of the tines 3, 4 incline outwardly with respect to the inner side edges from the lower ends of said tines and terminate in the ends of the body portion 1.

Formed integral with the rear end of the body portion 1 is a reduced cylindrical extension 5 of substantial length, and which has its outer end formed with a depending bifurcated projection 6. Mounted on the extension 5, as well as being fixedly secured therewith, is a handle member 7, constructed of wood, and having reduced end terminal portions 8, 9. Secured to the terminal portion 8 of the handle member 7, by the hold-fast devices 10, is a metallic sleeve 11, preferably of aluminum, and which has its outer end inwardly flanged, as at 12. The hold-fast device 10 further provides means for securing the handle member 7 to the extension 5, as said hold-fast device 10 passes through said extension. The head of the hold-fast device 10 is counter-sunk in the sleeve 11. The sleeve 11 projects a substantial distance from the inner end of the handle member 7 and has mounted therein a circular casing formed of two matching sections 13, 14, which surround the extension 5. The sectional casing forms an air chamber 15, and the front and end walls of said casing are provided with openings 16. The sectional casing is tightly confined between the flange 12 of the sleeve 11 and the inner end of the handle member 7. The sleeve 11 and sectional casing provide what may be termed a bulk heat 17' at the inner end of the handle member 7. Mounted on the reduced terminal portion 9 of the handle member 7 is a bulk head 17 similar to the bulk head 17' and through which projects the extension 5. The bulk head 17, handle member 7 and extension 5 are secured together by a hold-fast device 18 having its head counter-sunk in the cap 17. The flanged end 12 of the sleeve 11 is positioned a substantial distance from the rear or inner end of the body portion 1.

The comb-shaped member formed by the body portion 1 and the tines 2, 3 and 4 is adapted to be heated by any suitable means, and after heated sufficiently is enclosed within the guard to be presently referred to, and then applied to the hair for the purpose of removing the kinks therefrom. The guard with the heat applying element therein is drawn through the hair, due to the providing of the heat applying element with tines and the setting up of the guard, in a manner to be hereinafter referred to, with tines.

The guard element comprises a body portion V-shaped in vertical section. The said body portion includes a slotted bottom 19, a pair of slotted sides 20, 21, a closed front 22, a closed tapered back 23, and an open top. The height of the body portion of the guard element is greater than the height of the comb member of the heat applying element. The sides of the body portion of the guard element are secured to the tapered back wall

23 by hold-fast devices 24. The slots in each side wall of the body portion 25 of the guard are indicated at 26, and the slots in the bottom of the body portion 25 are indicated at 27 and merge into the slots 26. The slots 26 are spaced equi-distant from each other and the same arrangement is had with respect to the slots 27. The slots 26 are of greater height than the tines 2, and the material between the slots 26 forms tines 28 of greater height than the tines 2. The tines on one side of the body portion 25 oppose the tines on the other side of said body portion, and the opposed tines are connected together at their bottom, as at 29.

When the body portion 25 is set up relative to the comb member of the heat applying element, the tines 28 oppose certain of the tines 2, and the other of the tines 2 are exposed by the slots 26. The slotted body portion 25, in connection with the tines 2, 3 and 4, provides means to enable the device to slip readily through the hair and further for the heated body portion 1 and tines 2, 3 and 4 to heat the hair and remove the kinks therefrom, and such action is had without scorching or burning the scalp, due to the position of the guard with respect to the comb member.

For fixedly securing the comb member to the guard, when the latter encloses the former, the forward end of the comb member has an offset portion or tongue 30, which extends into a pocket 31 formed on the inner face of the front 22. The comb member is furthermore provided below the extension 5 with a tongue 32, which engages in a socket 33, formed on the inner face of the tapered back wall 23. The tongue 30 is formed integral with the forward end of the body portion 1 and the forward edge of the tine 3, and the tongue 32 is formed integral with a portion of the rear end of the body portion 1 and with the rear edge of the tine 4.

When the comb member is mounted in the guard, the extension 5 at the forward terminal portion thereof, or at its point of joinder with the rear end of the body portion 1, is seated in a groove 34 formed in the top edge of the back wall 23. Carried by the extension 5 is a latching device 35 for the purpose of maintaining the extension 5 in the groove 34 when the comb member is positioned within the guard or body portion 35.

The tapered back wall 23 terminates in a rearwardly extending arm 36, having a bifurcated rear end, as at 37. Extending in the bifurcated end 37 of the arm 36 is a tongue 38 which projects forwardly from an arm 39, having its rear end connected to the projection 6 by a pivot 40 carrying a controlling spring 41, which has one end, as at 42, bearing against the inner face of the projection 130

6 and its other end, as at 43, engaging the upper face of the arm 39. The tongue 38 swings on a vertical axis, which is provided by a pivot pin 44 therefor secured to the 5 rear end of the arm 36 and extending through the tongue 38. The rear end of the arm 36 is enlarged, as at 45, and the forward end of the arm 39 is also enlarged, as at 46, which act as a spacing means between the arms 36 and 39 and the handle member 7. The spring 41 acts to normally force the body portion 25 of the guard element in a direction from the comb member of the heat applying element. The arm 36 10 has secured to the inner side, at the rear terminal portion thereof, a stop bar 47 which projects against the inner side of the arm 39 and arrests the inward swinging movement of the arm 36 relative to the arm 39. The arms 20 39 and 36 provide a handle for the guard element.

When the comb member of the heat applying element is to be heated, the arm 36 and body portion 25 of the guard element 25 are swung at right angles with respect to the arm 39 and clear of the heating means for the comb member, whereby the guard will not become heated during the heating of the comb member.

30 It is thought that the many advantages of a kink removing implement for hair, in accordance with this invention, can be readily understood, particularly in view of the fact that it includes means to prevent the burning 35 or scorching of the scalp during the operation of the device, and although the preferred embodiment of the invention is as illustrated and described, yet it is to be understood that changes in the details of construction can be had which will fall within 40 the scope of the invention as claimed.

What I claim is:—

1. A device for the purpose set forth comprising a comb member for applying heat to the hair, a handle means extending rearwardly from said comb member, a slotted guard adapted to enclose said comb member, said comb member and guard provided with associated means for detachably connecting the comb member in enclosed position, a handle extending rearwardly from said guard, pivoted intermediate its ends, and further pivoted at its rear end with the rear end of said handle means.

55 2. A device for the purpose set forth comprising a comb member for applying heat to the hair, a handle means extending rearwardly from said comb member, a slotted guard adapted to enclose said comb member, said comb member and guard provided with associated means for detachably connecting the comb member in enclosed position, a handle extending rearwardly from said guard, pivoted intermediate its ends and further pivoted at its rear end with the rear

end of said handle means, and a controlling spring positioned between the rear ends of said handle and handle means.

3. A device for the purpose set forth comprising a slotted guard, a comb member adapted to be enclosed by said guard and further adapted to apply heat to the hair, said comb member provided with tongues extending into said guard, a handle means projecting rearwardly from the comb member, 70 means carried by the guard for detachably connecting the handle means therewith, a handle projecting rearwardly from the guard and pivotally connected at its rear end to the rear end of said handle means, 75 and a controlling spring interposed between the rear ends of said handle and handle means.

4. A device for the purpose set forth comprising a slotted guard, a comb member 85 adapted to be enclosed by said guard and further adapted to apply heat to the hair, said comb member provided with tongues extending into said guard, a handle means projecting rearwardly from the comb member, 90 means carried by the guard for detachably connecting the handle means therewith, a handle projecting rearwardly from the guard and pivotally connected at its rear end to the rear end of said handle 95 means, and a controlling spring interposed between the rear ends of said handle and handle means, said handle formed of a pair of sections pivoted at right angles with respect to the pivot between the rear end 100 of said handle and said handle means.

5. A device for the purpose set forth comprising a slotted guard, a handle extending rearwardly therefrom and formed with a pair of pivoted sections, a comb member 105 adapted to be positioned within said guard and further adapted to apply heat to the hair, an extension projecting rearwardly from said comb member, means for pivotally connecting the rear end of said extension to the rear end of said handle, the pivot between the handle sections disposed at right angles with respect to the pivot between said handle and extension, means for detachably connecting said comb member within said guard, and a handle member 110 fixedly secured to said extension.

6. A device for the purpose set forth comprising a slotted guard, a handle extending rearwardly therefrom and formed 115 with a pair of pivoted sections, a comb member adapted to be positioned within said guard and further adapted to apply heat to the hair, an extension projecting rearwardly from said comb member, means for pivotally connecting the rear end of said extension to the rear end of said handle, the pivot between the handle sections disposed at right angles with respect to the pivot between said handle and extension, 120 125 130

means for detachably connecting said comb member within said guard, a handle member fixedly secured to said extension, and means for limiting the movement in one direction of said handle sections relative to each other.

7. A device for the purpose set forth comprising a slotted guard, a handle extending rearwardly therefrom and formed 10 with a pair of pivoted sections, a comb member adapted to be positioned within said guard and further adapted to apply heat to the hair, an extension projecting rearwardly from said comb member, means for 15 pivotally connecting the rear end of said

extension to the rear end of said handle, the pivot between the handle sections disposed at right angles with respect to the pivot between said handle and extension, means for detachably connecting said comb member within said guard, a handle member fixedly secured to said extension, and means for limiting the movement in one direction of said handle sections relative to each other, and a bulk head secured to 20 the forward end of said handle member.

In testimony whereof, I affix my signature hereto.

WILLIAM H. SEABROOK, JR.
